UNITED STATES PATENT OFFICE

IRVING I. STONE, OF CHICAGO, ILLINOIS

CHUCK SPINDLE FOR WEB ROLLS

Application filed December 3, 1926. Serial No. 152,482.

This invention is supplemental to my Patent No. 1,605,997 granted November 9, 1926.

The principal object of the invention is to provide means for relieving the ends of the roll and the chucks at the ends from strain; also to provide a simple and inexpensive connection between the two chucks within the center of the roll for accomplishing the above mentioned purpose.

10 Other objects and advantages of the invention will appear hereinafter.

Reference is to be had to the accompanying drawings in which

Fig. 1 is a side view of a web roll located 15 in position on its centers; and

Fig. 2 is a side view of the two centering chucks thereof with the connecting device constituting a part of this invention shown in position and partly in section.

20 This invention is for use with a supporting device such as a reel rotatable about a shaft or other means for supporting the web roll.

The supporting arms 11 for a single web roll R are located at opposite sides of the machine 25 and they are provided with the usual steel spindles 12 fixed to the support on one side by a split collar 13 and having a center 14 for receiving the roll at that end. At the other end the arm 11 of the support is shown

30 as provided with a rack 18 with which a pinion 19 meshes. This pinion is on a shaft 20 on a bracket 21 and has a handle 22 fixed to the shaft for operating it to move the spindle back and forth, all as shown in my above 35 mentioned patent.

For supporting the roll R on the centers 14 I provide a pair of cylindrical chucks 25 which are similar to the chucks described in the above mentioned patent and have a circular flat flange at one end. Their shanks are cut down at the end to provide a square shoulder 26 and a cylindrical projecting end 27. These ends 27 fit into the opposite ends of a brass or other metal pipe or tube 28 which 40 is of such length as to fit up against the two

shoulders 26 at its opposite ends. The ends 27 are made to fit in the ends of the pipe rather closely. The pipe 28 strengthens the chucks and keeps them from having any lateral motion. In other words, each chuck acts as an anchor to the other to prevent the other from swinging out of the center. This connection across is very simple as it requires no special features on the pipe and merely the turning down of the ends of the chucks to form the 50 cylindrical projections entering the pipe and fitting it.

The chucks themselves may be made of solid pieces of metal or wood and they are placed in the ends of the spools of the rolls R 60 with the ends of the pipe engaging the projections 27. The pipe 28 and the chucks 25 have the same outside diameter and that fits tightly in the spool on the roll which is placed thereon by introducing the three elements of 65 this invention from the ends.

It will be noticed that these chucks have shanks of considerable length, as in my above patent, but that the firmness with which the roll is supported is greatly increased by this 70 additional tube. Therefore the strain on the chucks at the end of the roll is greatly reduced.

Although I have illustrated and described only a single form of the invention I am 75 aware of the fact that modifications can be made therein by any person skilled in the art without departing from the scope of the invention as expressed in the claim. Therefore, I do not wish to be limited to all the 80 details of construction herein shown and described, but it will be understood that I can still greatly reduce the diameter and weight of the web spools down to a minimum with the above invention.

85 What I claim is:—

A supporting means for a web roll comprising a pair of chucks having conical depressions for receiving conical supporting centers to be supported thereby and having cylin- 90

drical shanks of considerable length adapted to fit in the ends of the spool on which said web roll is wound, each chuck having a flange at the end engaging the end of said web roll and being provided at the opposite end with a square shoulder and with a cylindrical reduced projection extending therefrom; and a pipe with the same outer diameter as said chucks and the same inside diameter as the said projections, said pipe fitting tightly over said projections and against said shoulders to hold said chucks against lateral motion and to prevent strain.

In testimony whereof I have hereunto affixed my signature.

IRVING I. STONE.
